UNITED STATES PATENT OFFICE.

JAMES H. WITT, OF MERNA, NEBRASKA.

STOVE.

1,045,348.

Specification of Letters Patent.

Patented Nov. 26, 1912.

Application filed April 4, 1910. Serial No. 553,228.

To all whom it may concern:

Be it known that I, JAMES H. WITT, a citizen of the United States, residing at Merna, in the county of Custer and State of Nebraska, have invented certain new and useful Improvements in Stoves, of which the following is a specification.

This invention has relation to certain new and useful improvements in stoves.

10 The object of my invention is to provide a stove which while especially arranged to be used as a heating stove can also be used for cooking purposes.

15 A further aim of my invention is to provide a stove with two outstanding hollow ledges arranged to serve as warming shelves.

With the above and other objects in view, the present invention consists in the combination and arrangement of parts as will be 20 hereinafter more fully described and particularly pointed out in the appended claim, it being understood that changes in the specific structure shown and described may be made within the scope of the claim without 25 departing from the spirit of the invention.

In the drawings forming a part of this specification, and in which like numerals of reference indicate similar parts in the several views, Figure 1 shows a front view of a 30 stove embodying my invention. Fig. 2 is a rear view. Fig. 3 is a transverse sectional view. Fig. 4 is a middle lengthwise sectional view. Fig. 5 is a top view of the inner casing showing the damper arrangement.

35 The aim of my invention is to provide a stove, more particularly adapted to be used in the home, which, while proving particularly efficient as a heating stove, may also be 40 used for cooking and baking purposes.

In the accompanying drawings the numeral 5 designates the front plate of the stove which has the oven opening 6, the fire box opening 7 and the ash pit door 15.

45 The upper end of this plate is curved from a point approximately half way between the ends of the plate, the lower half section of the plate being rectangular. This plate is provided with the apertures 10 to receive the 50 damper rods, while below the oven opening 6 are the ears 12, the ears 13 being positioned at one side of the fire box opening. The ash pit has two sets of ears 14, arranged to carry the ash pit doors 15. The ears 13 carry 55 the door 7', while the ears 12 are arranged to receive the pins 17 carried by the oven

door 18, having the operating handle 19. Positioned above the oven opening is the latch 20 held upon the pin 21 and serving to securely hold the door 18 of the oven in a 60 closed position.

The rear plate 4 is constructed similar to the front plate with the exception that no fire box or ash pit opening is provided. The rear oven door 6' is detachably secured in a 65 manner similar to that described as attached to the front plate. Positioned between the fire box and ash pit opening, is the grate 23 of any approved type, so that wood or coal may be consumed in this stove. The two 70 end plates are connected by means of the casing forming plates 24 and 25. The casing plate 25, at opposite points, is provided with the outwardly directed portions 26 which form the ledges 27. These ledges 75 serve as warming shelves. Cavities are formed in these portions so that heat may pass therein. The upper rounded and dome shaped portion 28 of the casing is provided with two lid openings 29 covered by the lids 80 30, these openings being arranged to receive suitable cooking vessels. Centrally positioned between the ends of the casing portion 28 is the collar 31, arranged to receive the stove pipe 32. Suitable legs 33 hold the 85 stove above the floor.

Held between the end plates is the inner casing comprising the horizontal section 35 forming the bottom of the oven and the upper curved portion 36, this inner casing 90 being further provided with the flanges 37, arranged to receive an iron grate 38, supporting the baking and other culinary vessels placed within the oven. The ledges are braced by means of the bars 40, secured by 95 means of suitable rivets 39.

Secured to the upper portion of the inner casing near opposite ends are the flanges 42 and 43 held in parallel spaced relation. In Fig. 5 the position of the flanges is clearly indicated, the space between the flanges serving as a draft way. Each flange is provided with an ear 44 within which the damper trunnions 45 and the damper rods 46 are held. In their vertical or closed position the lower 100 edges of the dampers 48 are held against the attaching portions 48' of the flanges 42 and 43; these dampers, however, are illustrated as being held in a slightly inclined open position, as shown in Fig. 3. When the two 110 dampers are turned down, as shown in the figure last referred to, the heat and products

of combustion circle over the inner casing and find a ready escape through the stove pipe opening. However, when the dampers are closed the products of combustion are directed toward the end plates and in finding an escape they must pass through the draft ways around the flanges 42 and 43 and the dampers 48, in which condition the products of combustion pass squarely below the 10 lid openings within the outer casing.

When the stove is to be used merely for heating purposes, the oven doors 18 are entirely removed permitting a free circulation of air through the oven space. The stove 15 ledges at all times serve as warming shelves.

A stove constructed according to my invention may be used as a coal or wood burning stove, is simple and inexpensive in construction and durable and efficient in operation and can be used both as a heating and a 20 kitchen stove.

Having thus described my said invention what is claimed is:

25 A stove of the class described, comprising front and rear vertical walls having rounded

upper edges, side walls formed to correspond to the contour of the front and rear walls to form an arch shaped dome, said dome having an opening formed therein, outwardly extending shelves formed in the side 30 walls and adapted to be heated from within, a dome shaped oven arranged within the arch shaped dome portion of said stove, said oven extending from the front to the rear walls thereof, but having its side walls remote from the side walls of the stove to form draft ways, flanges arranged upon the top of said oven in proximity to the ends thereof, and dampers arranged in said flanges for controlling the draft ways, said flanges being positioned for permitting the products of combustion to pass thereover when said dampers are closed.

In testimony whereof I affix my signature, in presence of two witnesses.

JAMES H. WITT.
